UNITED STATES PATENT OFFICE

JOHN SGUERSO, OF BROOKLYN, NEW YORK

HAIR WAVER

Application filed September 12, 1931. Serial No. 562,481.

This invention relates to hair curling devices and more particularly refers to improvements in hair curlers of the type used in the art of permanent hair waving. In 5 current permanent waving practice, strands of hair are usually wound upon a metal curler so as to form a continuous helical coil extending longitudinally of the curler.

In some cases the strand of hair is flattened 10 and is spirally wound upon the curler so as to have its various coils superimposed upon one another. Before or after or both before and after the coiling operation, lotion is applied to the hair, said lotion usually consisting 15 of an alkaline solution, its effect being to "open" the hair. As a rule one end of the strand of hair is tied onto the curler before winding and the other end is tied after the winding is completed, and the coil thus 20 formed is usually tightened by the use of specially designed curlers. These usually consist of an outer tube about three to five inches long and an inner rod having a slotted end 25 projecting beyond the tube, said inner rod being rotatable in one direction and being restrained against rotation with respect to the tube in the opposite direction.

The starting end of the strand of hair is tied onto the slotted end of the rod and the strand is then coiled tightly around the tube, 30 tightening of the coil being subsequently obtained by turning the rod with respect to the tube in the winding direction.

In all the hair curlers which have heretofore come to my notice, the slotted end of the inner rod projects only about five-sixteenths of an inch beyond the tube, that is, just enough to provide means for inserting 35 a string or wire through the slot and tying it to said end. The coiling of the hair proper however is effected entirely along the tube and extends from the point of attachment of the hair strand to the slotted end of the inner rod to the opposite end of the tube, where the 40 other end of the hair strand is tied.

In another application for patent, entitled, Methods of permanent waving, co-pending herewith, Serial No. 355,398, is described a novel and improved method of permanently waving hair whereby a Marcel-wave effect is 50 obtained directly from the curler without requiring any subsequent finger waving operation.

This result is obtained by winding the hair upon the curler by forming a number of 55 twisted convolutions having a horizontal 8-shape and baking the hair while so wound. For this type of winding to be effective, it is necessary to tie the hair strand at the root end onto the curler and to wind each twisted 60 convolution partly at one side and partly at the other of the point of attachment.

Such a method of winding could not therefore be applied in connection with curlers in which the slotted end of the inner rod does 65 not project a substantial length beyond the tube. The total length of each twisted convolution is one and one-half inches more or less, and therefore the inner rod should project at least about from five-eighths of an inch 70 to an inch or more beyond the point at which the hair strand is attached thereto.

After a hair lock has been wound upon a curler or waver in the manner described above, it is necessary to set the hair under 75 tension before heat is applied thereto. Instead of rotating a part of the hair waver or curler, as is done when the lock of hair is coiled around the same, it is preferable to apply tension to the hair by expanding or 80 extending the hair waver in order to prevent the possibility of the 8-shaped convolutions being twisted out of shape.

Accordingly, the primary object of this invention is to provide a hair waver of a novel 85 and improved design comprising two coaxial members movable one with respect to the other so as to form an extensible structure, said structure being formed with means for fastening a lock of hair about midway 90

of the length of said structure, so as to permit said hair lock being wound partly upon one member and partly upon the other.

Another object of this invention is to provide a hair waver of a novel and improved design having its central portion barrel-shaped, and composed of two parts, one movable with respect to the other, said barrel-shaped structure preventing the hair convolutions from slipping and twisting out of shape when the said two parts are moved with respect to each other, in order to set the hair windings under tension.

A further object is to provide a novel and improved type of hair waver, composed of two parts together forming an axially collapsible and extensible structure having a barrel-shaped central portion, said structure being provided with easily operated means for causing the same to extend or contract.

A still further object is to provide a hair waver of the character specified, said hair waver comprising two parts movable one with respect to the other to form an extensible and collapsible structure, one of said two parts being provided with a portion rotatable about the axis of the waver and means for at times preventing the rotation thereof.

Other objects and advantages of the present invention will more fully appear as the description proceeds and will be set forth and claimed in the appended claims.

My invention is illustrated by way of example in the accompanying drawings, in which:

Fig. 1 is a side view partly sectioned of a hair waver embodying some of the principal features of my invention;

Fig. 2 is a longitudinal section of a hair waver similar to that shown in Fig. 1, having one of its axially movable members provided with an end portion rotatable about the axis thereof;

Fig. 3 is a side view of a hair waver, similar to that shown in Fig. 2, illustrating the beginning of the winding of a lock of hair thereupon;

Fig. 4 is a similar view illustrating the appearance of the lock of hair after it has been completely wound upon the waver so as to produce a Marcel-wave effect;

Fig. 5 is a view similar to that of Fig. 4, illustrating the application of the electric heater onto the wound lock of hair;

Fig. 6 is an end view of the hair waver and heater shown in Fig. 5;

Fig. 7 is a longitudinal section of another hair waver also embodying my invention in a different form;

Fig. 8 is a side view partly sectioned of another waver embodying some of the features of my invention;

Fig. 9 is an end view thereof;

Fig. 10 is another end view from the opposite end;

Fig. 11 is a detail front view in an enlarged scale of a spring washer used in connection with the device of Fig. 8;

Fig. 12 is a side view and Fig. 13 is a cross sectional view of an adjusting nut used in the device of Fig. 8;

Fig. 14 is a side view in enlarged scale partly broken away and sectioned of a knob removably insertable onto the split end of the hair waver shown in Fig. 8; and

Fig. 15 is an end view thereof.

The hair waver shown in Fig. 1 comprises two co-axial members 20, 21, each having a bulging inner end 22, 23, said bulging ends together forming a barrel-shaped central portion of the waver, as the drawings clearly show.

The inner end 23 of member 21 is provided with an axially extending recess 24 within which is inserted corresponding projection 25, outwardly extending in an axial direction from the inner end 22 of the member 20.

Member 21 is provided with an axial passage extending from the bottom of recess 24 to the outer end of said member, said passage receiving the stem portion 26 of an adjusting screw 27, inserted through a threaded axial opening 28 provided at the inner end of member 20.

Upon stem 26 is fixed a set collar 29, resting against the bottom of recess 24 and at the outer end of said stem is fixed a knob 30, by means of which said stem can be rotated.

It is thus seen that by virtue of this construction when knob 30 is rotated in one direction the two members will move away from each other in an axial direction, while when the knob is rotated in the opposite direction the two members 20, 21 will move towards each other, contracting the structure.

In Fig. 2 I show a hair waver of somewhat similar construction comprising two axially movable members 31, 32 having bulging inner ends, together forming a barrel-shaped central portion 33 of the waver, said two members being caused to move towards or away from each other by means of a knob 34, operating an adjusting screw 35 in the manner previously explained.

In the present case, member 31 has its outer end turned down to form a stem portion 36, having a threaded outer end 37. An axially perforated member 38 is rotatably mounted upon stem 36 in continuation of the outline of the inner end of said member 31, and a check nut 39 is screwed upon threaded end 37 of stem 36, said check nut being adapted to bear against the outer surface of member 38 so as to frictionally restrain the same against rotation.

The hair waver thus illustrated is, therefore, capable of expansion in an axial direction and is also provided with means for

setting under tension by rotation the outer end of a lock of hair wound thereupon in coiled form.

Both in the case of Fig. 1 and Fig. 2, the inner surfaces of the two axially movable members, facing each other, are normally separated by a gap indicated at 40 in Fig. 1 and 41 in Fig. 2, forming an annular groove through which it is possible to insert and fasten a thread or wire by means of which it becomes possible to tie onto the waver a lock of hair 42 shown in Fig. 3 at or near its root 43.

It is then possible to wind the lock of hair upon the waver in a series of convolutions, such as shown at 44 in Fig. 3, by running the lock or strand of hair across and around the waver alternately from one side of the point of attachment of the strand to the other, reversing the direction at each convolution. As a result, the strand of hair will ultimately take the shape shown in Fig. 4, in which a number of convolutions are superimposed upon one another, forming a substantially barrel-shaped mass of hair 45, extending at both sides of the point of fastening.

It is frequently desirable to produce a combined Marcel-wave-curl effect in which the body of the hair strand is Marcel-waved and the tip end is coiled so as to form a spiral curl. Such a result can be obtained by winding the hair about the waver in the manner explained up to one inch or more from the end, and then by winding the remaining portion in spiral or superimposed coils about the rotatable portion 38 of the waver, as shown at 46, tying the extreme end thereof onto said rotatable portion.

The hair should be tightly wound and an additional tension should be imparted to it after winding. The end 30 is, therefore, rotated so as to axially expand the waver without twisting the windings, as will be understood. Furthermore, in order to set under tension the coiled outer end of the strand of hair, rotatable member 38 is rotated in the winding direction and when a sufficient tension has been imparted to the hair, check nut 39 is turned so as to force it against the outer end of member 38, locking the same in position.

The hair is generally thoroughly moistened with a suitable alkaline lotion before or after twisting, or both. After the hair has been wound, tightened and moistened, it is covered with a piece of flannel or other suitable material, such as shown at 47, said flannel having first been impregnated with the lotion.

A protective pad, such as shown at 48, is also preferably applied onto the head directly opposite the hair waver, and the hair is then ready to be "baked" by a more or less prolonged application of a heating element thereto.

In the drawings, Figs. 5 and 6, the heating element is shown in the form of an electric heater of the clamp type, said heater comprising two jaws 49, 50, pivotally connected to each other at 51 and normally urged to their clamping position by a spring 52. Each jaw is internally provided with an electric resistance wire 53, which is covered by a protective shield 54.

A heating element is inserted over each wound strand of hair and the current is then turned on, each heating element being connected to a source of electric supply in any suitable manner (not shown).

Due to the fact that the hair windings are superimposed upon one another, the hair waver need not be very long. In fact, in practice I have found that a total length of two inches will do. This permits of placing the waver flat against the head, even though a large number of hair locks are treated at the same time.

In Fig. 7 I illustrate another axially extensible hair waver embodying my invention in a somewhat different form. In the same the body is composed of two halves 55, 56, together forming a barrel-shaped structure, said halves being inserted over and being axially movable with respect to a central tubular member 57.

Said member 57 is provided with two elongated slots 58, 59, through which project two rivets 60, 61, inwardly extending from parts 55, 56, respectively, so that the axial movement of said halves is limited by the length of said slots.

The outer end of both part 55 and part 56 is threaded to receive an adjusting screw 62, 63, operable by means of knobs 64, 65, the inner end of each screw projecting within the recess 66, 67, provided within said parts 55, 56, said recess registering with tubular member 57. Moreover, each screw carries at its inner end a block 68, 69, bearing against the ends of tubular member 57, as shown.

It will be seen that by virtue of this construction, if screws 62, 63 are turned so as to move blocks 68, 69 inwardly, this causes parts 55, 56 to move away from each other, thus setting under tension the hair windings 70. On the other hand, if the screws are operated in the opposite direction, blocks 68, 69 are moved away from the ends of tubular member 57 and parts 55, 56 can be moved towards each other by hand.

The barrel-shape feature of the waver can also be used when the waver is composed of two co-axial members rotatable one with respect to the other. Such a construction is shown in Figs. 8 to 13, in which the hair waver is composed of a half-barrel member 71, having a through axial bore and another half-barrel member 72, having a stem 73 extending through said bore, causing member 123

71 to be rotatably mounted with respect to member 72.

The outer end of member 71 is enlarged to form a knob 74 and is recessed to form a chamber 75 within which projects the threaded end 76 of stem 73. Between the face or shoulder 77 formed by stem 73 where it extends through member 72 and the inner surface 78 of member 71, is preferably inserted a washer 79, which may be of fibre or any other suitable material. Said washer is preferably of a diameter smaller than the adjoining portions of members 71, 72, thus forming therewith an annular groove 80, adapted to receive a thread or wire for fastening the strand of hair onto the waver.

Another flat washer 81 is placed about threaded end 76 of stem 73 and against the bottom surface of chamber 75.

Against said washer 81 bears the edge 82 of a convex spring washer 83, which also is inserted about the threaded end 76 of stem 73 and against said convex washer rests the inner surface of a pressure nut 84, screwed upon threaded end 76.

Threaded end 76 of stem 73 is preferably formed with two longitudinal grooves or keyways 85, 86, as shown in Fig. 11. In said keyways are inserted tongues 87, 88, inwardly projecting from opening 89 of washer 83, so that said washer is prevented from turning and will act as a lock washer for nut 84, causing said washer and said nut, together with washer 81, to turn bodily with stem 73 when the same is rotated with respect to part 71, or vice versa.

By virtue of the construction described, it will be seen that the pressure exerted by nut 84 against washer 83 tends at all times to restrain said two parts from rotation. The action of nut 84, washer 83 and washer 81 is in every way similar to that of a disk friction brake, the friction opposing the rotation of the two parts being developed between the inner surface of washer 81 and the bottom surface of chamber 75. By adjusting the position of nut 84 one way or the other, it is possible to decrease or increase the pressure exerted by washer 83 so that the restraining action of the friction brake may be adjusted at will.

After the lock of hair has been tightly wound about the waver in the manner above described, some additional tension is imparted to the windings by rotating parts 71, 72 with respect to each other in the direction in which the windings are made tighter. In order to hold member 72 with one hand while the other hand holds knob 74, the outer end of part 72 is made with a slot 90 and a removable knob 91 is inserted over said end, said knob being hollow, as shown at 92, so as to be adapted to receive the outer end of part 72, and being provided with a transversal

blade-like member 93 adapted to engage slot 90.

In practice, I have found the hair waver just described to be fairly satisfactory, but in view of the possibility of twisting the hair windings out of shape if an excessive rotation is imparted to either or both halves of the waver, I prefer to use the extensible type of waver shown in Figs. 1 to 6.

The constructional details of my device may vary from those shown without departing from the inventive idea; the drawings, therefore, will be understood as being intended for illustrative purposes only and not in a limiting sense.

I accordingly reserve the right to carry my invention into practice in all those ways and manner which may enter, fairly, into the scope of the appended claims.

I claim:

1. As a new article of manufacture, a hair waver consisting of an elongated body having a barrel shaped central portion, said body comprising two parts axially movable one with respect to the other, so as to set under tension the windings of a hair lock wound thereupon.

2. A hair waver comprising two co-axial members adjustably connected to each other so as to together form an axially extensible structure, said members being adapted to prevent slippage of hair windings wound upon said waver, when said members are moved away from each other to extend said structure.

3. A hair waver comprising two co-axial members adjustably connected to each other so as to together form an axially extensible structure, said members each having a bulging inner end and together forming a barrel shaped central portion of said waver.

4. A hair waver consisting of an elongated body having a barrel shaped central portion, said body comprising two parts movable one with respect to the other, so as to set under tension the windings of a hair lock wound thereupon, one of said movable parts having its outer end independently rotatable about the axis of said waver.

5. A hair waver consisting of an elongated body having a barrel shaped central portion, said body comprising two parts movable one with respect to the other, so as to set under tension the windings of a hair lock wound thereupon, one of said movable parts having its outer end independently rotatable about the axis of said waver and means for preventing rotation of said rotatable end after winding movement thereof.

6. A hair waver comprising two co-axial members adjustably connected to each other so as to together form an axially extensible structure, one of said members having its outer end independently rotatable about the axis of said waver.

7. A hair waver comprising two co-axial members adjustably connected to each other so as to together form an axially extensible structure, one of said members having its outer end independently rotatable about the axis of said waver, and means for preventing rotation of said rotatable end after winding movement thereof.
8. A hair waver comprising two co-axial members adjustably connected to each other so as to together form an axially extensible structure, said members each having a bulging inner end and together forming a barrel shaped central portion of said waver, one of said members having its outer end independently rotatable about the axis of said waver.
9. A hair waver comprising two co-axial members adjustably connected to each other so as to together form an axially extensible structure, said members each having a bulging inner end and together forming a barrel shaped central portion of said waver, one of said members having its outer end independently rotatable about the axis of said waver and means for preventing rotation of said rotatable end after winding movement thereof.
10. A hair waver comprising two coaxial members having a bulging inner end so as to together form a barrel shaped central portion of said waver, one of said members having an axially extending recess at its inner end, and the other having an axial extension at its inner end, registering with and insertable within said recess, the recessed member also having an axial passage extending from the bottom of said recess to the outer end of said member, an adjusting member having a stem portion rotatably inserted within said passage, the inner end of said adjusting member being threaded and being screwed into said axial extension, a knob mounted at the outer end of said stem for actuating said adjusting member to axially displace one of said members with respect to the other.
11. A hair waver comprising two coaxial members having a bulging inner end so as to together form a barrel shaped central portion of said waver, one of said members having an axially extending recess at its inner end, and the other having an axial extension at its inner end, registering with and insertable within said recess, the recessed member also having an axial passage extending from the bottom of said recess to the outer end of said member, an adjusting member having a stem portion rotatably inserted within said passage, the inner end of said adjusting member being threaded and being screwed into said axial extension, and a knob mounted at the outer end of said stem for actuating said adjusting member to axially displace one of said members with respect to the other, one of said members having a portion rotatable about the axis of the body thereof.
12. A hair waver comprising two coaxial members having a bulging inner end so as to together form a barrel shaped central portion of said waver, one of said members having an axially extending recess at its inner end, and the other having an axial extension at its inner end, registering with and insertable within said recess, the recessed member also having an axial passage extending from the bottom of said recess to the outer end of said member, an adjusting member having a stem portion rotatably inserted within said passage, the inner end of said adjusting member being threaded and being screwed into said axial extension, and a knob mounted at the outer end of said stem for actuating said adjusting member to axially displace one of said members with respect to the other, the member formed with an axial extension having its outer end rotatable about the axis of the body thereof.
13. A hair waver comprising two coaxial members having a bulging inner end so as to together form a barrel shaped central portion of said waver, one of said members having an axially extending recess at its inner end, and the other having an axial extension at its inner end, registering with and insertable within said recess, the recessed member also having an axial passage extending from the bottom of said recess to the outer end of said member, an adjusting member having a stem portion rotatably inserted within said passage, the inner end of said adjusting member being threaded and being screwed into said axial extension, a knob mounted at the outer end of said stem for actuating said adjusting member to axially displace one of said members with respect to the other, the member formed with an axial extension having its outer end rotatable about the axis of the body thereof, and means for preventing rotation of said rotatable end after winding movement thereof.
14. A hair waver comprising two coaxial members having a bulging inner end so as to together form a barrel shaped central portion of said waver, one of said members having an axially extending recess at its inner end, and the other having an axial extension at its inner end, registering with and insertable within said recess, the recessed member also having an axial passage extending from the bottom of said recess to the outer end of said member, an adjusting member having a stem portion rotatably inserted within said passage, the inner end of said adjusting member being threaded and being screwed into said axial extension, a knob mounted at the outer end of said stem for actuating said adjusting member to axially displace one of said members with respect to the other, the member formed with an axial extension having its outer end rotatable about the axis of the body thereof.

thereof, and a nut for checking rotation of said rotatable end.

15. A hair waver comprising two coaxial members adjustably connected to each other so as to together form an axially extensible structure, and means for axially adjusting either member with respect to the other without causing rotatory movement of either member.

16. A hair waver comprising two coaxial members adjustably connected to each other so as to together form an axially extensible structure, and threaded means for axially adjusting either member with respect to the other without causing rotatory movement of either member.

In testimony whereof I affix my signature.
JOHN SGUERSO.
